UNITED STATES PATENT OFFICE

138,060

DESIGN FOR A DRAWER FOR A REFRIGERATED LOCKER SYSTEM

William McKinley Baird, Chicago, Ill.

Application March 27, 1944, Serial No. 113,045

Term of patent 14 years

(Cl. D67—3)

To all whom it may concern:

Be it known that I, William McKinley Baird, a citizen of the United States of America, residing at 6541 Woodlawn Avenue, Chicago, Illinois, have invented a new, original, and ornamental Design for a Drawer for a Refrigerated Locker System, of which the following is a specification, reference being had to the accompanying drawing, forming a part thereof.

Referring to the drawing, Fig. 1 is a perspective

view of a drawer for a refrigerated locker system embodying my new design; Fig. 2 is a side elevational view; Fig. 3 is a rear elevational view; Fig. 4 is a bottom plan view and Fig. 5 is a top plan view of the same.

I claim:

The ornamental design for a drawer for a refrigerated locker system, substantially as shown.

WILLIAM MCKINLEY BAIRD.
